BY Chas. C. Townsend

ATTORNEY

UNITED STATES PATENT OFFICE.

ALLEN L. SHIRLEY, OF OAKLAND, CALIFORNIA.

DESIGN FOR A BANK.

60,739.

Specification for Design. Patented Mar. 28, 1922.

Application filed October 5, 1920. Serial No. 414,873. Term of patent 3½ years.

To all whom it may concern:

Be it known that I, ALLEN L. SHIRLEY, a citizen of the United States, residing at Oakland, in the county of Alameda and State of California, have invented a new, original, and ornamental Design for a Bank, of which the following is a specification, reference being had to the accompanying drawing, forming part thereof.

The figure is a perspective view of a bank showing my new design.

I claim:

The ornamental design for a bank, as shown.

ALLEN L. SHIRLEY.
